UNITED STATES PATENT OFFICE.

AUGUST NOGAR, OF READING, PENNSYLVANIA.

ENVELOP-OPENER.

1,191,816.

Specification of Letters Patent. Patented July 18, 1916.

Application filed November 15, 1915. Serial No. 61,577.

To all whom it may concern:

Be it known that I, AUGUST NOGAR, a citizen of the United States, residing at Reading, in the county of Berks and State of Pennsylvania, have invented certain new and useful Improvements in Envelop-Openers; and I do hereby declare the following to be a full, clear, and exact description of the invention, such as will enable others skilled in the art to which it appertains to make and use the same.

The invention relates to improvements in envelop openers.

The object of the present invention is to improve the construction of envelop openers and to provide a simple, practical and comparatively inexpensive device of strong and durable construction, capable of easy and rapid operation and to cut an envelop with a shearing action in a manner similar to a pair of scissors.

A further object of the invention is to provide an envelop of this character equipped with means for collecting and holding the severed portions of the paper and capable of enabling the same to be readily discharged into a waste basket or other receptacle.

With these and other objects in view the invention consists in the construction and novel combination and arrangement of parts hereinafter fully described, illustrated in the accompanying drawings and pointed out in the claims hereto appended, it being understood that various changes in the form, proportion and minor details of construction may be resorted to without departing from the spirit or sacrificing any of the advantages of the invention.

In the drawing Figure 1 is a perspective view of an envelop opener constructed in accordance with this invention, Fig. 2 is a side elevation taken from the other side of the device, Fig. 3 is a transverse sectional view taken substantially on the line 3-3 of Fig. 2, Fig. 4 is a similar view on the line 4-4 of Fig. 2, Fig. 5 is a detail sectional view illustrating the integral structure of the casing.

Like numerals of reference designate corresponding parts in the several figures of the drawing.

In the accompanying drawing in which is illustrated the preferred embodiment of the invention, the envelop opener comprises in its construction two pivoted members 1 and

2 tapered longitudinally and connected at their inner smaller ends by a bolt 3 or other suitable pivot. The members 1 and 2 are preferably constructed of sheet metal or other suitable material and the member 2 is in the form of a casing being composed of spaced sides 4 and 5 and a connecting end portion 6 located at the front or outer end of the device but the casing may be constructed in any other desired manner as will be readily understood and may be made of one or two pieces.

The sides 4 and 5 of the casing are spaced apart to receive the member 1 which is provided at its upper portion with a blade 7 extending along the upper edge of the member 1 and having a lower cutting edge 8 arranged to coöperate with the upper cutting edge 9 of a blade 10 carried by the pivoted member 2 and located within the upper portion of the casing. The blade 7 consists of a thin piece of steel detachably secured by screws 11 or other suitable fastening means to the pivoted member 1 and the blade 10 consists of a strip of steel secured by screws 12 or other suitable fastening devices to the inner face of the side 4 at the upper edge of the member 2 which is preferably provided with a longitudinal supporting flange 13 arranged in flush relation with the upper edges of the member 2 and formed integral with the side 4. The flange 13 provides a relatively large supporting surface on which to place the envelops to be opened.

In the operation of the device the member 1 is forced into the casing to cause the blades 7 and 10 to cut with a shearing action whereby envelops may be easily and quickly cut. The members are operated by pressure of the hand and they are automatically opened by springs 14 consisting of a coil and arms or extensions 15 and 16 which are secured to the members 1 and 2 by screws 17 and 18 or other suitable means. The outward movement of the members is limited by a lug 19 preferably formed integral with the member 1 at the lower edge thereof and arranged to engage the blade 10 at the front end thereof as clearly illustrated in Fig. 4 of the drawing. Any other suitable means may of course be employed for limiting the relative outward movement of the sections or members 1 and 2 of the device.

The member 1 is provided in its front or outer portion with a laterally extending thumb piece 20 curved as shown to present

a concave upper face to the thumb to enable the thumb of the operator to conveniently actuate the member 1 in the operation of the device. The member 2 is provided at 5 the bottom of the casing with a longitudinally disposed tubular portion 21 formed integral with the side 5 of the casing and communicating with the space between the sides of the casing. The tubular portion 21 10 curves from one side of the casing to the other and it constitutes the bottom of the casing and also serves as a rounded grip portion which rests in the fingers of the operator. The space between the sides of the 15 casing is open at the bottom to enable the severed portions of the envelop to be discharged into the tubular receptacle or portion 21 which also constitutes a chute for enabling the particles of the envelop to be 20 discharged into a waste basket or other receptacle. The tubular portion 21 is open at the front or outer end at 22 and is closed at the inner or rear end 23 by bringing it close to the casing.

25 In the use of the device the edge of the envelop is placed against the member 1 while resting on the supporting ledge or flange 13 so that the said member 1 serves as a stop for limiting the size of the piece cut from 30 the envelop. This will enable the device to cut with greater accuracy than a pair of scissors or shears and there will be no liability of accidentally cutting the contents of the envelop. Also by collecting the severed 35 portions of the envelop the device is adapted to prevent the litter which necessarily results from opening envelopes with ordinary shears or scissors.

The side 4 of the casing is preferably 40 open at 24 and the upper edge of the tubular portion 21 is arranged in spaced relation with the other side of the casing so as to afford ready access to the tubular portion or receptacle, should it be necessary to clean 45 the same.

What is claimed is:—

1. An envelop opener of the class described including two members pivoted together at one end of the device, one of the 50 members consisting of spaced sides slidably receiving the other member and open at the bottom, one of the members being extended

laterally beneath the other member and bent to form a longitudinal receptacle arranged to receive the severed portions of the envelop and also constituting a grip, and cutting edges carried by the said members. 55

2. An envelop opener of the class described including two pivoted members, one of the members consisting of a casing receiving the other member and having a longitudinal flange forming a supporting ledge, a blade mounted within the casing adjacent to the said flange, a coacting blade mounted on the other member of the envelop opener 60 and arranged to coact with the blade of the casing, and means carried by the last mentioned member and coacting with the blade of the casing for limiting the opening movement of the said members. 70

3. An envelop opener comprising two pivoted members, one of said members consisting of a casing provided at the bottom with a tubular portion forming a receptacle and constituting a grip and the other member 75 being slidable into and out of engagement and having means arranged to be engaged by the thumb of the operator.

4. An envelop opener of the class described comprising two pivoted members, 80 one of the members consisting of a casing composed of spaced sides and the other member being slidable into and out of the casing and having a stop located within the casing, a blade secured within the casing 85 and arranged to be engaged by the stop for limiting the relative outward movement of the said members, and a coacting blade mounted on the other member of the envelop opener. 90

5. An envelop opener comprising two pivoted members, one of the members consisting of a casing provided at the bottom with a tubular portion forming a receptacle and constituting a grip, the other member being 95 slidable into and out of the casing and having a laterally projecting thumb piece and cutting edges carried by the casing.

In testimony whereof I affix my signature in presence of a witness.

AUGUST NOGAR.

Witness:

BENNETT S. JONES.
